UNITED STATES PATENT OFFICE.

EVARISTE E. TALBOT, OF FALL RIVER, MASSACHUSETTS.

TAKE-UP MOTION FOR LOOMS.

Application filed May 27, 1924. Serial No. 716,117.

My invention relates to take-up motions for looms, for winding cloth over the breast beam and on to the cloth-roll as fast as the filling is inserted and the cloth is woven.

5 In the takeup-motion, the speed at which the cloth is drawn over the breast-beam, governs the number of picks per inch that are placed in the cloth; the greater the speed, the fewer the picks per inch, and 10 vice versa.

It is common practice among loom makers to employ, in their takeup-motions, a train of several gears, some of which are change gears, one a "change pinion gear," 15 and a compound "change gear." To enable a loom to weave cloths varying in number of picks per inch, say from 26 picks to 149 picks, there must be something like 80 different combinations of the several gears 20 making up the train; that is, each combination must be made up of one "change pinion gear," either one of 16 teeth, or one of 20 teeth; one of 50 "change gears," varying in 25 number of gear teeth from 14 to 65; and three permanent gears having fixed numbers of gear teeth.

Accompanying each particular make of looms, is a table showing the various number of picks per inch that may be woven, 30 and the particular combination of "change gear," and "change gear pinion," required to produce the desired number of picks per inch of cloth woven; so that, knowing the number of picks demanded, the combination 35 of gears is at once disclosed.

It is to be noted, next, that when a loom is stopped on account of the filling running out, or breaking, the momentum of the loom generally carries the loom at least two picks 40 before it stops; consequently, if there is nothing to prevent it, the takeup-motion will operate for those two picks, although there is no filling being placed in the cloth; and when the loom is started and the filling 45 is required, a "thin place" will appear in the cloth.

But when the filling runs out or is broken, a well-known release mechanism operates a specially designed pawl which allows the 50 driving gear of the train to be turned back, any two teeth, i. e. the distance it was carried forward during the two picks by the momentum of the stopping loom, so that the

cloth is in the position it was, when the filling ran out or was broken.

Now it frequently happens that the sand roll, under the direct tension of the warp threads and the cloth, cannot be turned back at all, because of the number and weight of the gears constituting the train. In such 60 event, the above-mentioned "thin place" in the cloth appears, because there is not enough tension in the cloth and warp to bring about the necessary "let-back" of the sand roll and its heavy operating gears.

Now it is one of the objects of my invention to insure this "let-back" of the sand roll, and hence, the return of the cloth to the position it was in when the filling ran out or broke, without limiting the range 70 in the usual number of picks per inch of cloth, determined by the takeup-motion, say, between 44 and 176 picks per inch. I attain this object by providing (1) a train of three gears as substitutes of the several formerly 75 used, thereby reducing their number, weight and rolling friction; and (2) by providing two or more separate sources of power, each operating at different speeds, so that any particular train of three gears giving a par- 80 ticular number of picks per inch of cloth, may be driven at any one of two or more different speeds, and hence correspondingly vary the number of picks per inch; all with the result, that the reduction of the pick 85 capacity of the takeup-motion,—due to fewer gears in the train than formerly, permitting the desirable "let-back" and absence of "thinness" in cloth,—is restored to normal capacity, by giving any one of the sev- 90 eral different speeds, to each combination of gears in the train.

By reason of my invention, instead of requiring, for example, 80 different combinations of several gears to bring about any 95 number of picks between say 44 and 176 picks per inch, only about 23 different combinations of three gears, are requisite; and instead of using 50 "change gears" and one of two "change gear pinions," I use one of 100 34 "change gear pinions" and three "change ratchets." I thus dispense with, say, 30 gears, their cost, and their presence in the combination train of gears.

Numerous other advantages will appear 105 hereinafter.

In the drawings illustrating the principle of my invention and the best mode now known to me of embodying the same in operative structure,

5 Fig. 1 is an end view of my invention, operated by either a cam or a driving gear, on the cam shaft.

Fig. 2 is a like view showing the connection between the lay-sword of the loom, and 10 one arm operating the pawl of the takeup-motion; the lay-sword being a third source of power.

Fig. 3 is a plan, and

Fig. 4 is a front view of the said motion.

15 Fig. 5 shows in end elevation said motion operated by the cam on the cam-shaft.

Fig. 6 shows in enlarged detail, in elevation, a well-known form of detent and let-back pawl holding a ratchet, operated by a 20 driving latch.

A rigid take-up lever 1, Fig. 1, is pivoted on a stud 2 fastened to the sand roll stand 3 of the loom. It has two arms 1^a and 1^b. Its arm, or "elephant trunk" 1^a extends forwardly and downwardly towards the base of the loom, the bottom end portion 4 of the arm 1^a being pivotally connected to a link 5 whose opposite end portion is connected to an eccentric 6 on a driven gear 7, by a strap 8, the driven gear, meshing with a driving gear 9 fixed to a cam-shaft 10, and being in diameter one-half that of the driven gear. That the eccentric may be adjusted in relation to the center of the driven gear, the latter has a slot or groove 11 diametrically cut in its face, and in this slot is movably mounted a key formed radially upon the back of the eccentric. A lock-bolt 12 passes through a radial adjusting slot 13 in the eccentric, and through a hole in the driving gear. By this arrangement of parts, the eccentric may be adjusted to give the desired throw. Also upon the cam-shaft 10, Figs. 1 and 5, is a cam 14 which operatively engages 45 a filling-cam member 15, pivoted on said stud 2, Figs. 1 and 5; the working end portion of which member is slotted, as is likewise the free end portion of arm 1^b of the take-up lever 1, whereby by means of the 50 binding screw and nut 16, Fig. 5, said filling cam member 15 may become fixedly, as in Fig. 5, or loosely, as in Fig. 1, secured to the arm 1^b of the take-up lever 1.

Attached to the takeup-lever 1 is a driving latch or pawl 17, so shaped as to engage a ratchet 18, which is removably mounted upon a pinion stud 19 in the sand-roll stand 3. Also removably mounted on this stud, is a "change gear" pinion 19' which meshes 60 with a gear 20 on a sand-roll 21. The number of teeth on each gear of this train is assumed for the sake of illustration, to be as follows:—110 on the ratchet 18; 16 on the pinion 19 and 78 on the sand-roll gear 20. 65 The sand-roll gear is not changeable; there

are 34 change gear pinions, having from 10 to 44 teeth; while there are three change ratchets having respectively 110, 112 and 114 teeth, or more if desired.

The ratchet 18 is designed to be moved 70 forward one tooth at a time, by the pawl 17; but as each change ratchet has a different number of teeth and a different diameter, from each other ratchet, the movement of the link 5 connecting the "elephant trunk" 75 or takeup-arm 1, and the eccentric 6 on the driven gear 7, operated by the driving gear 9 on the cam shaft 10, must be so controlled that it will cause the pawl to engage only one tooth of whatever change ratchet may 80 be in use. This is done by adjusting the eccentric 6 to give the required throw to cause the link 5 and takeup-arm 1 to move driving latch 17 enough to engage only one tooth of the ratchet upon each revolution of 85 the eccentric.

The detent and let-back pawl 22, Figs. 1 and 6, which I employ, but was not invented by me, is well-known in the art, and manufactured and sold by Kilburn, Lincoln Ma- 90 chine Company of Fall River, Mass.

It comprises a lever pivoted upon a stud 50, on the frame, and a channelled gravity latch 51 for controlling the ratchet 18; one arm 52 being operated by suitable mechanism, not shown, when a filling thread breaks, or runs out; while the other arm 53 serves as a guideway for the channelled latch 51, which, in normal position, as shown in Fig. 6, protrudes through an opening in the 100 end portion of the latch 51, the free end portion of the latch being adapted to ride over, say, two teeth of the ratchet 18, and engage the second tooth and serving as a detent; and when so doing, a lock tooth 57 on arm 105 53 engages a lock bar 58 of the latch, and prevents any movement of the latch along the arm 53.

A pin 56, through ears in the latch, permit a slight rotary movement of the arm 53 in 110 relation to the latch; while a shoulder 61 limits a longitudinal movement of the gravity latch, by an engagement with the edge 62 of the opening in the latch 51; the distance between said edge and said shoulder 115 being such that when a filling thread breaks or runs out, the arm 52 will be moved to the left, thereby causing the lock tooth 57 to move up and away from the lock bar 58, without lifting the free end of the latch out 120 of engagement with the tooth of the ratchet 18; so that while the driving latch 17 moves the ratchet ahead, say, the distance of two teeth, the gravity latch 51, without disengaging the ratchet, follows down the guide-arm 53, until the edge 62 abuts the shoulder 61; and when the latch 17 moves again to push ahead the ratchet, the cloth tension causes the ratchet 18 to reverse its rotary movement, the gravity latch 51 being forced 125 130

upward along the guide-arm 53 until the gravity latch abuts the shoulder 59 and thus brings the ratchet 18 to a stop and in the position it was when the filling thread broke 5 or ran out.

When the filling thread is replaced or repaired, the arm 52 moves to the right and the let-back pawl 22 returns to normal position; the guide-arm 53 moving to the left 10 about the pivot 50 and the pin 56, until its tooth 57 engages the lock bar 58, and the detent let-back pawl 22 is returned to its working position; that is, to serve as a detent and hold the ratchet 18 while the latch 15 17 is moving back two teeth to move again the ratchet 18.

In order that the takeup-motion may be driven at a speed different from that derived by using either the cam 14 or the gear 20 9, on the cam-shaft 10, the takeup-lever arm 1 may be connected to the lay-sword 23, as shown in Fig. 2. To the lower end portion 4, is pivoted a link 24, the free end of which is threaded and removably secured by a nut 25 25 to a yoke 26, the free end of the yoke being adjustably secured in a slotted member 27 fixed to the lay-sword 23.

It is to be recalled that the lay moves forward and back once for each revolution of 30 the main shaft, not shown, that is, once for each pick; that the cam-shaft revolves once every two picks; that the latter has one-half of the speed of the former; and that as the driving-gear 9 on the cam-shaft is, in diameter, one-half that of the driven-gear 7, 35 the speed of rotation of the latter is one-half that of the driving-gear, and hence, that of the cam-shaft; so that for each pick of the loom, the lay 23 operates forward and 40 back, once; the cam 14 on the cam-shaft revolves once, for each two picks; and the driven-gear 7 once, for each four picks.

We will assume that the combination of 45 the train of gears and the source of power and speed are such as will cause the takeup-motion to move the cloth over the breast beam on to the sand-roll 21, at a speed that will produce the desired number of picks per inch of cloth woven; and that the filling 50 cam-member 15, Fig. 1, has been disconnected from the takeup-lever by a loosening of the binding nut and bolt 16 in the respective slots in said levers; the source of power being the driving-gear 9 upon the cam-shaft 10. For each two revolutions of 55 the cam-shaft 10, the driven gear 7 revolves once; the link 5, and takeup-lever 1 move forward and back; the driving-latch 17 snaps over the next ratchet tooth and moves 60 the ratchet 18 forward; the detent and let-back pawl 22 dropping into its next ratchet tooth space to hold the ratchet during the next movement of the driving-latch. These 65 movements are repeated for every two revolutions of the cam-shaft. Resulting from

these movements of the ratchet, are the movements of the change-pinion-gear 19, the sand-roll gear 20, the sand-roll 21; and the cloth having the desired speed to produce the wished-for picks per inch of cloth woven. 70

The momentum of the moving parts of the loom is likely to cause the takeup-motion to advance the cloth and warp, say two picks, with no filling, before the loom and takeup-motion stop. However, the moment 75 the filling breaks or runs out, suitable mechanism, not illustrated, operates, and causes the detent and let-back pawl 22 to engage and allow the ratchet 18, in the manner already described, to be reversed the desired 80 distance required for two picks by the tension of the cloth and warp-threads acting through the sand-roll 21, and the train of gears including the ratchet. The cloth has thus been returned to the position it was in 85 when the filling broke or ran out, and is ready for the next pick with filling. This "let back" of cloth and warp and gearing, is assured, because of the reduction in number, weight and friction of the train of 90 gears.

As the source of power and speed, and the combination of gears of the train, are suitable for a certain number of picks per inch 95 of cloth, it is plain that if the source of power is changed, so that the speed of the train of gears is doubled, the takeup-motion will cause the speed of the cloth and warp to be woven, to be doubled, and there will be one-half the number of picks per inch that were given before. For example, if the link 5, Fig. 1, connecting the "elephant trunk" arm 1^a, and the driven gear, be removed, and the filling-cam-lever member 15 and takeup-lever-arm 1^b be secured together by 100 the binding nut and bolt 16, Fig. 5, passing through their respective slots, and the loom be started, then the cam 14 on the cam-shaft 10 being the source of power and speed, will act upon the combined filling-cam member 15 and takeup-lever 1, and cause the driving latch 17 to move the ratchet 18, gearing, sand-roll 21, and cloth twice as fast as before, and reduce the number of picks per inch, one-half. 105

Still further, should it be desired to reduce the number of picks per inch one-half again, then this result may be obtained by using as a new source of power having twice the last speed, the lay-sword 23, Fig. 2. To put the takeup-motion shown in Fig. 1 in proper condition to accomplish this result, the filling-cam member 15 and the takeup-lever 1 must be disconnected, and for the link 5 must be substituted the link 24, connected to the takeup-lever arm 1^a, and to the lay-sword 23, as shown in Fig. 2. 110

Also, if with the combination of gears shown, it were wished to have, for example, three-quarters of the number of picks per inch produced by the driving and driven 115 120 125 130

gears upon the cam-shaft, then by providing a driven gear having a diameter of three-quarters of that of the driven gear shown, that is the ratio of

$$\frac{\text{the diameter of the driven gear}}{\text{the diameter of the driving gear}} = \frac{3}{2},$$

the desired number of picks per inch would be obtained.

10 An examination of the following table will make the foregoing statements plain:

15 *Table showing how a single combination of three gears can, by changing its source of power, obtain as many different numbers of picks per inch as there are different sources of power and speed.*

20	Source of power	Ratio of number picks per inch to each ratchet tooth moved.					Picks per inch.
		Ratchet teeth.	Pinion teeth.	Sand roll teeth.			
25	Main shaft, or lay-sword—one pick during each revolution, or forward and back movement of lay-sword.	1 to 1	110	16	78	44	90
	Cam or cam-shaft— $\frac{1}{4}$ speed of main-shaft—2 picks during each revolution of cam on cam shaft.	2 to 1	110	16	78	88	
30	Eccentric on driven gear— $\frac{1}{2}$ speed of gear on cam-shaft—four picks during each revolution of driven gear.	4 to 1	110	16	78	176	95
	Eccentric on driven gear—ratio $\frac{3}{4}$ speed of driving gear on cam shaft—3 picks during each revolution of driven gear.	3 to 1	110	16	78	132	

35 Should the combination of gears be, for example, 114, 15, 78, and the various sources of power and speed be applied as above, then there would result respectively 48, 96, 192 and 144 picks per inch.

40 In short, by having available three or more different sources of power and speeds, I can with the same train of three gears weave three or more separate pieces of cloth each having a different number of picks per inch of cloth:—that is, without, as heretofore, having to change the combination of gears to produce each different number of picks.

45 Obviously, by using a train of three gears, two of which are changeable, a person cannot get the necessary number of different picks per inch that can and must be obtained, as formerly, with a train of five gears, two of which are changeable; but it is true, that by using three or more different sources of power and speed, and a train of three gears, two of which are changeable, I do get the necessary number of different picks, and at the same time, without the great number of 50 changeable gears heretofore required.

55 In fine, by means of my invention, there is much greater assurance that there will be no “thin places” in the woven cloth; the number of changeable gears will be greatly reduced; the need of changing the combination

of gears is greatly reduced; the gearing is easily accessible for changing; the necessity of purchasing and having what is now a great number of change gears for each loom, is obviated.

70 While I have derived, as here shown, my power and different speeds from the crank-shaft, the cam-shaft, cams and gearing, I do not limit myself to them particularly, for my idea is to combine the driving-latch of a takeup-motion with any source of power whereby the latch may be given different required speeds of action upon its ratchet.

75 This takeup-motion may be used in weaving borders, the cloth and warp, and hence the takeup-motion, being stationary during the period required to put in the number of picks used to make the border. That the takeup-motion may be stopped for a certain number of picks, a dobby, not shown, is 80 connected by a wire 28, to the top portion 29 of the pawl 17, and, by the operation of the dobby, the pawl is caused to disengage and later engage, the ratchet seasonably to stop and start the takeup-motion, before and after the formation of the border.

85 A safety latch 30 is ready to engage and limit a reverse movement of the ratchet 18, should a filling thread break or run out, and the let-back pawl 22, and the pawl 17, for any reason, be out of engagement with the ratchet 18. The latch is pivoted at 31. Its rear arm 32 is heavier than its toothed arm 30^a, its downward movement being determined and limited by a vertical adjusting screw 33 by means of which the latch more or less deeply engages the ratchet. The ratchet, moving normally ahead, slides over the teeth of the latch, which is out of engagement with the screw 33, but should the ratchet reverse its movement, the weighted arm of the latch would fall and stop upon the top of the adjusting screw, one of the teeth of the latch being ready to engage a tooth of the ratchet, and stop its reverse 95 movement. But it will be obvious that the amount of the reverse movement of the ratchet depends upon the position of the safety-latch and the adjusting screw; and that by lowering or by raising the screw, 100 the latch is given greater or less movement, and correspondingly limits the reverse movement of the ratchet. In practice it is adjusted to permit the same rear movement of the ratchet as is allowed by the left-back pawl 22 when the filling thread breaks, say two teeth. The result is that the safety-latch never interferes with the action of the let-back pawl, but is ready to duplicate the 105 action of the let-back pawl, whenever the latter fails in its action. It may be said that, 110 in actual use, the let-back pawl fails to act, say once a day. The safety-latch therefore 115 obviates results due to the failure of the action of the let-back pawl. This apparatus 120

125 130

constitutes one of the features of my invention.

Desiring to protect my invention in the broadest manner legally possible, what I claim is:—

1. A takeup-motion having a sand-roll; a train of gears comprising a sand-roll gear, a change-pinion gear, and a change-ratchet gear; a ratchet pawl; a source of power, acting at one speed; a source of power acting at a different speed; means for connecting and disconnecting said ratchet pawl from one source of power; and means for connecting and disconnecting said ratchet pawl 10 with said other source of power, for operating said sand-roll at any one of said different resulting speeds; and detent and let-back mechanism; the chain of gears and sand-roll reversing their rotation, during the release of the detent and let-back mechanism from the change-ratchet gear, by the tension of the warp threads of cloth being woven and engaging the sand-roll.
2. A takeup-motion for a loom, having a sand-roll; a train of gears comprising a sand-roll gear; a change-pinion gear and a change-ratchet; a ratchet pawl; a driving-shaft; a cam and a driving gear thereon, a driven gear meshing with the driving gear, 25 each having a different diameter; a takeup-lever having two arms; a filling cam member, operated by said cam; a link operatively connected to one end of one of said arms, and that may be eccentrically connected to and disconnected from said driven gear; means for connecting said link to, and disconnecting said link from, said lay; means for rigidly connecting and disconnecting said filling cam member and the other of said arms; means for operatively connecting said ratchet pawl with the first of said arms, whereby the pawl may 30 drive the ratchet at any one of three different speeds.

and eccentrically connected to said driven gear; means for rigidly connecting, and disconnecting, said filling cam member and the other of said arms; means for operatively connecting said ratchet pawl with the first of said arms, whereby the pawl may drive the ratchet of the chain of gears at different speeds.

3. A takeup-motion for a loom, having a sand-roll; a train of gears comprising a sand-roll gear; a change-pinion gear and a change-ratchet; a ratchet pawl; a lay; a cam shaft; a cam thereon; a driving gear on said cam shaft; a driven gear meshing with said driving gear, each having a different diameter; a takeup-lever having two arms; a filling cam member, operated by 45 said cam; a link operatively connected to one end of one of said arms, and that may be eccentrically connected to and disconnected from said driven gear; means for connecting said link to, and disconnecting said link from, said lay; means for rigidly connecting and disconnecting said filling cam member and the other of said arms; means for operatively connecting said ratchet pawl with the first of said arms, whereby the pawl may 50 drive the ratchet at any one of three different speeds.

In testimony whereof I hereunto affix my signature.

EVARISTE E. TALBOT.
